CLASP-STUD.

1,387,230.

Specification of Letters Patent.

Patented Aug. 9, 1921.

Application filed June 6, 1921. Serial No. 475,263.

To all whom it may concern:

Be it known that I, GEORGE T. BRANNIGAN, a citizen of the United States, residing at Bridgeport, county of Fairfield, State of Connecticut, have invented an Improvement in Clasp-Studs, of which the following is a specification.

This invention relates to clasp-studs such as are used in garment supporters, and the like, and has for its object to provide a stud consisting of a head, shank and base, which shall be formed mechanically from a blank of wire.

With this end in view I have devised the novel wire stud which I will now describe, referring to the accompanying drawings, forming a part of this specification, and using reference characters to indicate the several parts.

Figure 1 is a view in elevation illustrating the use of my novel stud in a garter. Fig. 2 is an elevation of the stud removed from the garter and on an enlarged scale. Fig. 3 is a perspective view of the stud detached. Fig. 4 is a section on the line 4—4, in Fig. 1. Fig. 5 is a plan view of a modified form of stud detached. Fig. 6 is an end elevation of the form of stud shown in Fig. 5 and Fig. 7 is a perspective view of a second modification.

Reference numeral 1 denotes the band of a garter which may be of any ordinary material or design, and 2 the ordinary metallic clasping loop, which in use engages the stud as clearly shown. The clasping loop is attached to the band in any ordinary or preferred manner as by means of a loop 3 of textile web, and the stud is carried by a longer loop 4 of textile web which is also attached to the band.

The stud, in the form illustrated in Figs. 1 to 4 inclusive, comprises a head 5, a shank 6 and a base 7. The head, which lies approximately parallel to the plane of the base, is formed from a portion of a wire blank at one end thereof, the end being indicated at 8, and the blank being curved to form an approximately circular head of the required size. Just under the head the blank is bent inwardly at 9 and then downwardly to form one half 10 of the shank, it being noted that the head overhangs the shank. At the lower end of the shank the blank is bent outwardly, as at 11, at approximately a right

angle and is then curved and recurved at 12 to form one end of the web slot 13. The other end of the slot 13 is formed by curving and recurving the blank again at 14. The blank is then extended diagonally across under the shank as shown at 15 and approximately an equal distance on the other side of the shank is curved and recurved at 16 to form one end of the other web slot 17. It is then again curved and recurved at 18 to form the other end of slot 17, turning inwardly toward the shank, and the end is then turned upwardly to form the other half 19 of the shank and terminates within the head at 20. It will thus be seen that the shank is comprised of two strands of wire 10 and 19 lying in contact, and that the two ends of the blank are protected and so located as not to interfere with the placing on the stud of the yielding collet 21 employed to complete it.

The collet 21 is molded from rubber, the upper end being enlarged as at 22, and is provided with a recess which receives the head 5 of the stud, the recess being preferably large enough to receive the head so that the latter will lie wholly below the upper end of the collet.

The stud is attached to web loop 4 by passing one end of the loop downward through slot 13 then across and upward through slot 17, then around backward and under the stud, the ends of the loop being stitched or otherwise secured to the garter band.

In the modified construction illustrated in Figs. 5 and 6 the end of the blank on the half 19 of the shank instead of being inserted within the curve of the other end of the blank, is curved in the opposite direction from the direction in which the said other end is curved, but in a similar manner, to form a second section 23 of the head similar to the first section. Otherwise the modified form is the same as that illustrated in Figs. 1 to 4 inclusive. In this form the two curved ends provide a larger head for the stud as a whole than in the first form.

The form of stud illustrated in Fig. 7 is the same as that shown in Figs. 1 to 4 inclusive except that the end of the blank which is bent to form the head does not terminate, as at 8, in abutting relation to the downward curve of the wire from the head to the shank, but is itself bent downwardly

at 8^a and terminates at 8^b above the outwardly bent portion 11 of the base. Because of this arrangement there is no possibility of the free end of the wire interfering with the 5 application of the collet.

Having thus set forth the nature of my invention, what I claim herein is—

1. A clasp-stud formed from a wire blank and comprising an approximately circular 10 head formed at one end of the blank, the blank being then bent inward and downward to form half a shank, the blank being then bent outward and curved and recurved twice on opposite sides of the shank to form web 15 slots, and then upward to complete the shank.

2. A clasp stud formed from a wire blank and comprising a head formed from a length of the blank at one end thereof, the blank being then bent downward to form half of 20 a shank, the blank being then curved and recurved to form web slots, and then bent upward to complete the shank.

3. A clasp stud formed from a wire blank and comprising a head formed from a length 25 of the blank at one end thereof, the blank being then bent downward to form half of the shank, the blank being then curved and recurved to form web slots, and then bent upward, and terminating within the head. 30

In testimony whereof I affix my signature.
GEORGE T. BRANNIGAN.
